CLAIM

The ornamental design for a bra, as shown and described.

DESCRIPTION

FIG. 1 is a front view of a bra showing my new design in a first strap configuration in use;

FIG. 2 is a rear view thereof;

FIG. 3 is a perspective view of the bra of FIG. 1 shown in a second strap configuration in use on a mannequin bust;

FIG. 4 is a perspective view of the bra of FIG. 1 shown in a third strap configuration in use on a mannequin bust;

FIG. 5 is a left side view thereof;

FIG. 6 is a right side view thereof;

FIG. 7 is a front view of the bra in FIG. 3;

FIG. 8 is a front view of the bra in FIG. 4;

FIG. 9 is a rear view of the bra in FIG. 3;

FIG. 10 is a rear view of the bra in FIG. 4; and,

FIG. 11 is a rear view of the bra of FIG. 1 shown in a fourth strap configuration in use on a mannequin bust.

The short dashed broken lines in the drawings depict features of the bra that form no part of the claimed design. The long dashed broken lines outline of the partial mannequin figure in FIGS. 3-11 assists in illustrating how the bra may appear when in a position of use, but forms no part of the claimed design.
